UNITED STATES PATENT OFFICE.

FRED B. RHODES, OF WASHINGTON, DISTRICT OF COLUMBIA.

DESIGN FOR A MEDAL.

No. 38,555.

Specification for Design.

Patented May 14, 1907.

Application filed April 13, 1907. Serial No. 368,121. Term of patent 3½ years.

To all whom it may concern:

Be it known that I, FRED B. RHODES, a citizen of the United States, residing at Washington, District of Columbia, have invented a new, original, and ornamental Design for Medals, reference being had to the accompanying drawing, forming a part thereof.

sents the reverse face of a medal showing my design.

I claim:

The ornamental design for a medal, as shown.

FRED B. RHODES.
